[57] CLAIM

The ornamental design for a long handle V-line brush, as shown and described.

DESCRIPTION

FIG. 1 is a side elevational view of a long handle V-line brush of this invention, with an opposite, side elevational view, taken with the brush of FIG. 1 is rotated 180° about its longitudinal axis, being a mirror image thereof;

FIG. 2 is a side elevational view of the long handle V-line brush of FIG. 1 when rotated about its longitudinal axis 90°; FIG. 3 is a side elevational view of the brush of FIGS. 1 and 2 when the brush is rotated 180° about its longitudinal axis from the view in FIG. 2;

FIG. 4, 5, 6, and 7 are cross-sectional views taken respectively at cuts 4—4, 5—5, 6—6, and 7—7 in FIG. 1;

FIG. 8 is an end elevational view taken from the brush end of the long handle V-line brush of FIG. 1;

FIG. 9 is an end elevational view taken from the handle end of the long handle V-line brush of FIG. 1;

FIG. 10 is a side elevational view of a second embodiment long handle V-line brush of this invention, with an opposite, side elevational view taken when the brush of FIG. 10 is rotated 180° about its longitudinal axis, being a mirror image thereof;

FIG. 11 is a side elevational view of the long handle V-line brush of FIG. 10 when rotated about its longitudinal axis 90°;

FIG. 12 is an end elevational view taken from the brush end of the long handle V-line brush of FIG. 10; and,

FIG. 13 is an end elevational view taken from the handle end of the long handle V-line brush of FIG. 10.
